UNITED STATES PATENT OFFICE

JOHN B. PICARD, OF TOLEDO, OHIO, ASSIGNOR TO THE NATIONAL SUPPLY COMPANY, OF
TOLEDO, OHIO, A CORPORATION OF OHIO

PUMPING JACK

Application filed November 20, 1930. Serial No. 496,866.

My invention relates to pumping jacks designed particularly for oil wells, but adapted to other apparatus.

The principal object of this invention is to provide a pumping jack with links connected between the jack frame and the pump rod so as to provide an approximately straight line travel of the pump rod.

Referring to the accompanying drawings, Fig. 1 is a side elevation of a portion of a pumping jack containing my invention, parts being broken away; Fig. 2, an end elevation of the upper portion of Fig. 1 shown on an enlarged scale; Fig. 3, a side elevation of the upper left hand portion of Fig. 1, the scale being the same as in Fig. 2; Fig. 4, a diagrammatic view showing the position of the links and adjacent parts when the pump rod is at its extreme positions; Fig. 5, a section on the line 5—5 on Fig. 2; Fig. 6, a section on the line 6—6 on Fig. 2; Fig. 7, a view similar to Fig. 2, but showing a modification; Fig. 8, a side view of Fig. 7; and Fig. 9, a section on the line 25 9—9 on Fig. 7.

On the drawings, 1 designates a vertical standard or post upon which the oscillating frame 2 is pivoted by means of the horizontal pin or shaft 3. The frame comprises the 30 upper horizontal member 4, the vertical member 5 and the diagonal member 6 which are connected together to form a triangular frame. The members 4 and 5 are jointed at a right angle and the pin 3 is located near 35 this angle. The lower portion of the member 5 has attached thereto the pull rod 7 designed to be connected to a suitable reciprocating power device for causing the oscillation of the frame 2 on the pin 3.

40 8 designates the upper portion of a pump having the pump rod 9. The end of the member 4 farthest from the pin 3 is provided with a pair of bearings 10 for the trunnions 11 projecting from the sides of 45 the upper end of the link 12. The lower end of the link 12 has the oppositely-extending trunnions 13 which receive the upper ends of the members 14 of the link 15. 16 is a swivel-block having trunnions 17 in the 50 lower ends of the members 14. The pump

rod 9 extends upwardly through the swivel-block 16 and is supported thereby in any suitable manner, as by the clamps 18 surrounding the pump rod, the lower clamp resting on the top of the swivel-block and the upper clamp resting upon the lower one.

The end of the frame supporting the link 12 is provided with an abutment 19 pendent on the member 4 and having its outer face or edge 20 substantially at right angles with the member 4 and standing, when the member 4 is horizontal, substantially across an imaginary horizontal plane which includes the pin 3. The lower end of the link 12 adjacent to the face 20 is provided with the 60 lug or stop 22 which engages the face 20 when the frame 2 is at or above its central or horizontal position. The thickness of the lug 22 is such that the upper ends of the link members 14 cannot engage the face 65 20, because their ends would by rocking engagement with the face 20 soon wear a hole in it and make the apparatus inefficient or 70 inoperative.

The lower ends of the link members 14 75 are provided with the lugs 23 adjacent to the face 20. The ends of the lugs nearest to the face 20 are connected together by the cross-bar 24 which is secured to the lugs and engages the face 20 when the frame 2 is 80 at or above its horizontal position, as shown on Fig. 1. The lugs 23 and the bar 24 serve as a stop carried by the link 15 prevent the swivel-block 16 from rocking engagement with the face 20 which engagement would 85 soon injure or destroy the said face.

The link 12 has in its outer or right hand face the longitudinal groove or channel 21 extending from end to end of the link to receive the pump rod 9, the groove being 90 deep enough to allow the axial center line of the rod to lie on a line connecting the axial centers of the trunnions 11 and also in a line connecting the axial centers of the trunnions 13 when the links 12 and 15 are 95 vertical as shown in Figs. 1 and 3. The groove allows the link 12 to move to the right away from the rod 9 as the frame member 4 moves above its horizontal position as shown in dotted lines in Fig. 4. 100

The axial center of the rod 9 lies also on a line connecting the centers of the trunnions 17. When the lug 22 is in engagement with the abutment 19 as shown, the centers of the trunnions 11, 13 and 17 lie in an arc drawn from the center of the pin 3. A horizontal line drawn from the center of the pin 3 when the arm is substantially in its central position lies between the pivots 13 and 17 and at right angles to the axial center of the rod 9. Thus the pivot 17 will remain substantially in vertical alinement with the axial center of the rod as it travels during the swinging of the arm between its central position shown in Fig. 1 and its upper position shown at the upper part of Fig. 4. With the frame member 4 horizontal, the stop bar 24 rests against the abutment 19 and the centers of the trunnions 13 and 17 are in a vertical plane which includes the axial center of the pump rod 9. If the pump rod 9 is allowed to descend, the abutment moves slightly to the right while the trunnions 17 move downwardly substantially vertically. After the abutment has moved downwardly for some distance and at about the time the trunnions 11 move outwardly so as to be in substantially vertical alinement with the pump rod 9, the abutment moves slightly away from the upper ends of the link 15 so that the trunnions 13 continue downwardly substantially vertically. Also the trunnions 11 move downwardly in a substantially vertical plane standing in the axial center of the pump rod. When the frame has moved to lower the pump rod to its lowest position the parts would be as shown in the lower portion of Fig. 4. Here all of the trunnions, 11, 13, and 17 are shown one above the other in a substantially vertically plane which includes the vertical central line of the pump rod. During the downward movement of the pump rod from its said central position, the arc movements of the trunnions are so small as to be negligible and the lateral movements of the pump rod are so small as to permit the pump rod to move through the pump without any added appreciable friction due to such lateral movements.

The link 12 has in its outer or right-hand face the vertical groove or channel 21 extending from end to end of the link to receive the pump-rod 9, the groove being deep enough so that when the links 12 and 15 are both vertical the axial center of the rod intersects imaginary lines connecting the axial centers of the trunnions 11 and 13. The axial center line of the rod also intersects an imaginary line connecting the trunnions 17. The rod 9 is held in a groove in the swivel-block by the cap 25. The groove 21 allows the link 12 to move to the right away from the rod as the frame member 4

moves above its horizontal position as shown in Fig. 4. The links 12 and 15 are in tandem and are suspended from the trunnions 11 which are parallel with the trunnions 13 and 17, the trunnions all being horizontal and at right angles with the frame member 4 and parallel with the pivot pin 3.

On Figs. 7, 8, and 9 a modification is shown wherein the stop 22 of Figs. 1, 3, and 5 is replaced by the enlargement 26 on the lower end of the link 12, this enlargement by engaging the face 20 prevents the oscillating upper end of the link members 14 from engaging with the face 20 of the abutment 19. The lower ends of the link members 14 have the enlargements 27 which engage the face 20 to keep the oscillating swivel-block 16 from contacting with the said face and injuring the same.

This application is in part a continuation ⁸⁵ of my application Serial Number 423,348, filed January 25, 1930.

I claim:

1. In a pumping apparatus, a pumping arm oscillatable on a horizontal axis, a pendent link pivotally supported by the arm, a vertically-reciprocating pump-operating rod, a pivotal connection between the lower end of the link and the upper end of the rod, an outwardly-facing abutment carried by the arm adjacent to and opposite the inner face of the link, and means carried by the lower portion of the link and engaging the abutment and spacing the upper end of the said pivotal connection from the abutment, the spacing means contacting with the outer face of the abutment, only when the arm is above a predetermined position.

2. In a pumping apparatus, a pumping arm oscillatable on a horizontal axis, a pendent link pivotally supported by the arm, a vertically-reciprocating pump-operating rod, a pivotal connection between the lower end of the link and the upper end of the rod, an outwardly-facing abutment carried by the arm adjacent to and opposite the inner face of the link, and means carried by the lower portion of the link and engaging the abutment and spacing the upper end of the said pivotal connection from the abutment, the spacing means contacting with the outer face of the abutment, only when the arm is above its horizontal position.

3. In a pumping apparatus, a pumping arm oscillatable on a horizontal axis, a pendent link pivotally supported by the arm, a vertically-reciprocating pump-operating rod, a pivotal connection between the lower end of the link and the upper end of the rod, an outwardly-facing abutment carried by the arm adjacent to and opposite the inner face of the link, and means carried by the lower portion of the link and engag-

ing the abutment and spacing the upper end of the said pivotal connection from the abutment, the spacing means contacting with the outer face of the abutment, only 5 when the arm is above its horizontal position and near thereto.

4. In a pumping apparatus, a pumping arm oscillatable on a horizontal axis, a pendant link pivotally supported by the arm, 10 a second link pivotally supported by the first link, a swivel-block carried by the lower end of the second link, a vertically-reciprocating pump-operating rod attached to the swivel-block, an outwardly-facing abutment carried by the arm adjacent to and opposite the inner face of the lower ends 15 of the links, and means carried by the lower portion of the links and adapted to engage the outer face of the abutment and space the upper end of the second link and the 20 swivel-block from the abutment, the spacing means contacting with the abutment when the arm is above a predetermined position, thereby giving the said rod a substantially 25 straight-line travel.

5. In a pumping apparatus, a pumping arm oscillatable on a horizontal axis, a pendant link pivotally supported by the arm, a second link having its upper end pivotally 30 supported by the lower end of the first link, a swivel-block pivotally supported by the lower end of the second link, a vertically-reciprocating pump-operating rod supported by the swivel-block, the pivots connecting the links together and connecting 35 the second link to the swivel-block, and being parallel with the said axis, an outwardly-facing abutment carried by the arm adjacent to and opposite the lower ends of 40 the links, and means carried by the lower portion of the links and adapted to engage the outer face of the abutment and space the upper end of the second link and the swivel-block from the abutment, the spacing means 45 contacting with the abutment when the arm is above a predetermined position, thereby giving the said rod a substantially straight-line travel.

6. In a pumping apparatus, a pumping arm oscillatable on a horizontal axis, a pendant link pivotally supported by the arm, a second link pivotally supported by the first link, a swivel-block carried by the lower end of the second link, a vertically-recipro- 55 cating pump-operating rod attached to the swivel-block, an outwardly-facing abutment carried by the arm adjacent to and opposite the inner face of the lower ends of the links, the outer face of the abutment being sub- 60 stantially at right angles with the arm, and means carried by the lower portion of the links and adapted to engage the outer face of the abutment and space the upper end of the second link and the swivel-block from 65 the abutment, the spacing means contacting

with the abutment when the arm is substantially horizontal and above the same, the parts being proportioned to give the rod a straight-line travel as the arm oscillates.

In testimony whereof, I hereunto affix my 70 signature.

JOHN B. PICARD.
